COMBINED CHAIR AND TABLE

Filed Oct. 24, 1927

Inventor

Bruce B. Kline
By his Attorneys
Merchant and Kline

UNITED STATES PATENT OFFICE.

BRUCE B. KLINE, OF MINNEAPOLIS, MINNESOTA.

COMBINED CHAIR AND TABLE.

Application filed October 24, 1927. Serial No. 228,116.

My invention has for its object the provision of a combined chair and table, and more particularly a child's combined chair and table that can be separately interlocked by simple and highly efficient means after a child is placed in the chair to prevent separating movement of the chair and table or a lifting movement of the table from the chair so as to prevent the child from getting out or falling out of the chair.

The table is especially adapted for holding the playthings of a child and is designed to prevent the same from falling from the table.

To the above end, generally stated, the invention consists of the novel devices and combinations of devices hereinafter described and defined in the claims.

In the accompanying drawings, which illustrate the invention, like characters indicate like parts throughout the several views.

Referring to the drawings:

Fig. 1 is a perspective view of the combined chair and table;

Fig. 2 is a fragmentary detail view partly in plan and partly in horizontal section taken on the line 2—2 of Fig. 1; and

Fig. 3 is a fragmentary detail view partly in elevation and partly in section taken on the line 3—3 of Fig. 2.

The combined chair and table are indicated by the numerals 4 and 5, respectively.

Said chair 4 has a pair of arms 6, the outer longitudinal edges of which are in diverging relation, as best shown in Fig. 2. These longitudinal edges of the arms 6 are also transversely beveled, as best shown in Fig. 3.

The table 5 has a flat top 7 and a depending apron 8. Said top 7 has an upstanding marginal flange 9 that is continuous except for an intermediate gap 10 at the front of the table. The table top 7 at the gap 10 is cut away at 11 substantially to the apron 8.

A pair of seats 12 for the arms 6 are formed in the lower edge portions of the apron 8 at the gap 10. These seats 12 have horizontal dovetailed interlocking engagement with the outer longitudinal edges of the arms 6, as indicated at 13, that hold the chair and table interlocked against separating movement away from each other. The arms 6 and seats 12 have further separable interlocking engagement at the longitudinal edges of said arms, as indicated at 14, and

hold the chair and table interlocked to prevent lifting movement of said table in respect to said chair.

To interlock the chair and table, said table is placed over the arms 6 thereof with said arms in the seats 12 and then said chair and table are separated to cause the arms 6 to interlock with the seats 12 by a wedge action, as indicated at 13. The interlocking engagement between the arms 6 of the chair 4 and the table 5 securely holds said table and chair against separating movement away from each other. This same movement of the chair 4 and table 5 away from each other causes the arms 6 to further interlock with the table 5, as indicated at 14, and thereby connect said chair and table so as to prevent lifting movement of the table 5 in respect to the chair 4. To separate the chair 4 and table 5 it is only necessary to move said table toward the chair 4 and then lift said chair from the arms 6.

By reference to Fig. 3 it will be noted that there is clearance between the upper faces of the arms 6 and the seats 12, as indicated at 15, so as to permit the legs of the table to rest on the floor. The apron 8 between the seats 12 is reduced in width at its lower edge portion, as indicated at 16, to afford additional clearance between the seat of the chair 4 and the lower edge portion of the apron 8.

When a child is placed in the chair 4 and said chair separably interlocked to the table 5, as indicated in Fig. 1, it is impossible for the child to separate the chair and table either by movement of the chair 4 of the table 5 away from each other or by a lifting movement of the table 5 in respect to the chair 4, thus preventing the child from getting out or falling out of the chair 4.

To separate the chair 4 and table 5 it is only necessary to push one thereof toward the other and then lift the table from the arms of said chair. The interlocking engagement between the arms 6 and seats 12 is such that there is no danger of a child being pinched therebetween and there are no parts to get out of order. Any wear between the arms 6 and seats 12 will be automatically taken up. The cut away portions 11 and 16 permit a child to sit very close to the table 5 and the flange 9 prevents the child's playthings placed on the table top

7 from being pushed therefrom onto the floor where the child cannot reach the same.

What I claim is:

1. A combined chair and table, each of 5 which is independently supported in respect to the other, said chair having a pair of arms, the outer longitudinal edge portions of which are in forwardly diverging relation to each other, said table having seats 10 with which the diverging edge portions of the arms are arranged to engage with a wedge action produced by a movement of the chair and table away from each other.

2. The structure defined in claim 1 in 15 which the outer longitudinal edge portions of the arms and their seats have dove-tailed interlocking engagement to prevent the table from being separated from the chair by a lifting movement.

20 3. A combined chair and table, each of which is independently supported in respect to the other, said chair having a pair of

arms, the outer longitudinal edge portions of which are in forwardly diverging relation to each other, said table having an 25 apron with an intermediate reduced portion, and seats in the apron at the ends of its reduced portion with which the diverging edge portions of the arms are arranged to engage with a wedge action produced by a movement 30 of the chair and table away from each other, said outer longitudinal edge portions of the arms and their seats have dove-tailed interlocking engagement to prevent the table from being separated from the chair 35 by a lifting movement.

4. The structure defined in claim 3 in which there is clearance between the upper faces of the arms of the chair and apron to prevent the table from being supported on 40 said arms.

In testimony whereof I affix my signature.

BRUCE B. KLINE.
